UNITED STATES PATENT OFFICE.

GLENN R. HOFFMAN, OF SPRINGFIELD, ILLINOIS, ASSIGNOR TO HOFFMAN MANUFACTURING COMPANY, OF SPRINGFIELD, ILLINOIS, A CORPORATION OF ILLINOIS.

TRANSMISSION BAND.

Application filed March 5, 1923. Serial No. 622,914.

To all whom it may concern:

Be it known that I, GLENN R. HOFFMAN, a citizen of the United States, residing at Springfield, in the county of Sangamon and State of Illinois, have invented certain new and useful Improvements in Transmission Bands; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to transmission bands, and has for its object to provide improved features of construction in the removable ear of the band whereby it can be readily attached and detached to facilitate the removal of the transmission band from its drum and its replacement without interference from the transmission gears of the Ford type of car.

To the accomplishment of the foregoing and such other objects as may hereinafter appear the invention consists in the features hereinafter particularly described and then sought to be clearly defined by the claims, reference being had to the accompanying drawing forming a part hereof, and in which—

Figure 1 is a perspective of a removable ear formed according to this invention;

Figure 2 is a perspective of a portion of the metallic strap or band forming a part of the transmission band;

Figure 3 is a vertical longitudinal section through the removal ear and portion of the transmission band strap and lining.

In the drawing the numeral 1 designates the removable ear of a transmission band constructed according to the present invention. The shank of the ear is formed with slots 2 having enlarged portions 3, and to one end is attached by a rivet 3^a or otherwise, preferably so as to swivel although it may not swivel, a metal strap 4, preferably spring metal, formed with a depending flange or hook 5. The transmission band illustrated comprises a metal strap or band 6 having a lining 7 of woven fabric or other material and provided with headed studs 8 designed to enter the slots 2 and formed with a slot 9 designed to receive

the hook or flange 5 of the strap 4 when the ear is attached in operative position to the transmission band. The ear is attached by placing it so that the heads of the studs 8 will enter the enlarged ends of the slots in the ear when the ear is slid so as to bring the studs into the narrower portions of the slots with the heads bearing down on the top face of the shank of the ear thus preventing spreading apart of the ear and band. At the same time the flange of the plate or strap 4 is caused to enter the slot 9 of the band 6, in which it may be held by the spring tension of the plate and thus the ear will be prevented from slipping longitudinally on the transmission band. When the ear is to be disengaged from the band the hook or flange of the plate 4 will be pried out of the slot 9 of the band 6 and the ear slipped back from the free end of the band so as to bring the heads of the studs in the enlarged portions of the slots 2 when the ear can be lifted from off the band, and thus leave the transmission in condition to be removed from its drum without interference between it and the transmission gears of the Ford type of car. The device is simple and efficient in construction and manipulation.

Having described my invention and set forth its merits what I claim is:

1. A transmission band provided with a removable ear formed with slots having enlarged ends and provided at one end with a plate projecting beyond the end of the ear and having a down-turned lip or flange, and a band provided with headed studs to fit in the slots of the ear and formed with a slot to receive the lip projecting from said plate.

2. A transmission band provided with a removable ear formed with slots having enlarged ends and provided at one end with a spring plate projecting beyond the end of the ear and having a depending lip, and a band provided with headed studs to fit in the slots of the ear and formed with a slot to receive the lip of the spring plate.

In testimony whereof I affix my signature in presence of two witnesses.

GLENN R. HOFFMAN.
